PULL TAB FOR A CAN OR THE LIKE

Nick S. Khouri, Chicago, Ill., assignor to Continental Can Company, Inc., New York, N.Y., a corporation of New York

Filed May 27, 1966, Ser. No. 2,449

Term of patent 14 years

(Cl. D58—26)

FIG.1

FIGURE 1 is a top perspective view of a pull tab for a can or the like, showing my new design;

I claim:

The ornamental design for a pull tab for a can or the like, as shown and described.
